Application August 25, 1934, Serial No. 741,388

18 Claims. (Cl. 305—10)

This invention relates to an improved endless track mechanism, and more particularly to an improved track link construction in self-laying endless track mechanism of a track-type vehicle, 5 such as a tractor.

Introduction and general description

Each link forming part of an endless track mechanism of a track-type tractor, is usually 10 formed of an intermediate full width rail portion, and end portions of reduced width adapted to be pivotally connected with reduced width end portions of adjacent links to provide a rail in which there are joints between adjacent links, 15 each joint including a pair of longitudinally spaced gaps. The endless track includes a pair of rails thus formed, and turns about a final drive sprocket and a front idler wheel. Heretofore, the rail extremities of the reduced width end portions 20 of the links were so formed as to leave comparatively wide rail gaps in the joints between adjacent links; and they were generally perpendicular to the longitudinal line of the rail. In such prior construction, when a weight bearing track roller 25 travels over the gaps in a rail joint, it can not find support on more than half full rail width throughout its entire travel over the joint. This is so because if the reduced width end portions are each of half full rail width, then obviously 30 when the roller travels over either joint gap, it is supported on only a half full rail width. Should one of the reduced width end portions be of less than half full rail width and the other greater than half full rail width, the roller is supported 35 on the end portion of less than half full rail width as it travels over the gap at the side of such less than half full rail width end portion.

Also, in such prior construction, when a weight bearing track roller travels over one gap, its entire weight will be supported for a period of time 40 solely on the reduced width end portion overlapping an end of such gap. Thus, such reduced width end portion will have a region where it is subjected to greater roller pressure per unit area 45 than the unit pressure on the full width rail portion of the link. As a result, such region will wear more rapidly, and the rail surface of such region will be lowered below the plane of the rail surface of the full width rail portion of the link. 50 This results in pounding of the roller against portions of the links which bound the gap, thereby creating destructive forces causing premature breakdown of the joint. As each joint includes a plurality of such gaps, it is seen that the roller 55 will be supported solely on one link end portion of

reduced width as it travels over one gap, and then solely on another reduced width end portion as it travels over another gap. The transference of weight from one reduced width end portion to another causes a shearing effect between adjacent pivotally connected links, having a destructive action on the members pivotally connecting the track link assemblies. 5

The link of our invention is so constructed as to overcome the disadvantages pointed out above, 10 and provide a joint of long life. In our improved construction, the reduced width end portions of the links have their rail extremities so formed as to be oblique with respect to the sides of the link, and underlap the full width rail portion of 15 an adjacent link, to provide more than half full width rail support for a track roller throughout its entire passage over a joint without widening the rail width of the joint beyond the full width rail portion of the links. The surfaces under the 20 full width rail portion of a link adapted to be underlapped by the oblique surfaces on the reduced width end portions of adjacent links, are arranged to have an obliqueness complementary 25 and substantially parallel, to that on such reduced width end portions, and thus form diagonal wiping joints in which, by virtue of such underlapping, the wearing qualities of the joint are maintained, as the rail wears. In the embodiment of the invention illustrated, the wide gaps 30 which previously existed in links prior to our invention are filled by end bosses or rail end projections, each of which has an oblique rail edge, and an oblique surface at its extremity. 35

It has been found that cast metal links are 40 not satisfactory for long life; and, as a result, forged metal links have been relied upon to provide material of desirable strength and durability. Forging of a metal link having the inwardly extending oblique extremities at the ends of the 45 reduced width end portions of the link, presents the problem of removal of the link from the forging die. Our invention, therefore, includes the construction of a track link having the advantageous features previously discussed but which can be forged without manufacturing difficulty. We accomplish this by placing each end portion 50 of the rail forging line which extends over an oblique extremity on a reduced width end portion, closely adjacent and substantially parallel 55 to a side face of the link, with one forging line end portion at one side of the link and the other at the opposite side of the link. Our manner of forging enables final construction of the link without subsequent special machining operations; 60

only the conventional machining operations being necessary. Should one desire to employ a non-forged link, the constructional shape of our link can still be utilized to provide for the advantageous features of our invention.

Objects of invention

The invention has for its objects, among others, the provision of an improved:

10 Endless track mechanism constructed to promote long life and efficient operation;

Endless track mechanism of economical construction free of excess weight;

15 Rail joint between adjacent pivotally connected links of the track, formed to provide ample rail surface engageable with track rollers, to enhance wearing qualities of the track and thereby provide long life;

20 Rail joint capable of accomplishing the foregoing described object, and which is still of substantially full rail width to form part of a rail of full uniform rail width throughout;

25 Rail joint over which the track rollers can travel without pounding against edges of the joint when the track and rollers have become worn;

30 Track link constructed to cooperate with adjacent links to provide any of the foregoing described objects;

35 Forged metal track link to provide any of the foregoing described objects.

Having enumerated some of the objects and having described principles of construction of our invention, we shall now refer to the drawings for 35 a more detailed description of our invention, as embodied in one of its forms.

Description of figures

40 Figs. 1 through 6 illustrate the track construction.

Fig. 1 is a side elevation of a portion of the endless track.

Fig. 2 is a fragmentary plan view taken as indicated by line 2-2 in Fig. 1.

45 Fig. 3 is a fragmentary section taken in the plane indicated by the line 3-3 in Fig. 1.

Fig. 4 is a vertical transverse section taken in the plane indicated by the line 4-4 in Fig. 1.

50 Fig. 5 is a vertical transverse section taken in planes indicated by the lines 5-5 and 5'-5' in Fig. 1; the left half of Fig. 5 being taken in planes indicated by line 5-5 and the right half being taken in planes indicated by line 5'-5'.

Fig. 6 is a vertical transverse section taken in 55 the plane indicated by the line 6-6 in Fig. 1.

Figs. 7 through 10 illustrate the track link construction, a right-hand link being selected for illustration.

Fig. 7 is a right side elevation of the link.

60 Fig. 8 is an elevational view of the inside of the link.

Fig. 9 is a sectional view taken in the plane indicated by the line 9-9 in Fig. 7, the inside and outside parting lines of the forging being 65 shown in phantom lines.

Fig. 10 is a sectional view taken in the plane indicated by the line 10-10 in Fig. 7, the inside and outside parting lines of the forging being shown in phantom lines.

70 Endless track

Each endless track mechanism of a track-type tractor generally includes an endless self-laying track supported around an associated track frame, by means of a front idler wheel mounted

at the front of the track frame and a driving sprocket at the rear thereof; the weight of the tractor being transmitted to the ground stretch of the track through a plurality of weight bearing track rollers running on spaced rails of the 5 track. The driving sprocket serves to propel the tractor over the endless track, and to pick up the track and feed its upper reach forwardly over the front idler wheel which guides the re-laying thereof. If desired, the upper stretch of the track 10 between the front idler and drive sprocket can be supported by suitable track carrier rollers.

Figs. 1 through 6 illustrate the construction of a track link assembly of our invention, a plurality of which when pivotally connected together form the endless track. Such assembly comprises track shoe 106 secured to the outer edges of left-hand link 107 and right-hand link 108, by cap screws 109. Lock washers 110 are preferably interposed between the cap screw heads and the ground face of the track shoe. Grouser 111 (Fig. 1), integral with shoe 106, is formed to retain its earth penetrating ability after considerable wear. The ground-engaging end 111' of the grouser is substantially flat or non-pointed; and its sides 111a diverge with gradual taper toward the base of the grouser which is not materially wider than end 111'. Hence, the width of end 111' does not increase unduly as grouser 111 wears, which would be the 30 case with a relatively sharp pointed end heretofore employed. Cap screws 109 have non-circular or flat sided heads to facilitate fastening thereof by a suitable instrument, such as a wrench. Each head is formed with convexly 35 shaped end surface 112; the contour of each surface 112 being initially such as to correspond to the contour, which wear on the head would cause during operation of the track. Such contour is preferably substantially spherical. As a result, 40 ground drag which might be caused by the heads when the track is new is reduced to a minimum.

45 Track links 107 and 108 of each assembly are symmetrical with respect to each other, to thereby form left-hand and right-hand links, respectively. As can be seen more clearly from Figs. 2 and 4, one pair of reduced width end portions (preferably the front end) of a pair of links forming a link assembly are at the inner sides of the links, and are overlapped or embraced by 50 outer reduced width end portions at the rear of the links of the adjacent pair of links, to provide full width rail joints of butt-lap construction. The inner reduced width end portions are connected by bushing 113 press-fitted in such portions; and the outer reduced end portions are connected by pin 114 journaled in bushing 113 to provide the pivotal connection between adjacent pairs of links. From Fig. 4, it will be seen that pin 114 is longer than bushing 113, so that 55 the pin ends can be press-fitted in the outer reduced width end portions. Bushing 113 and pin 114 are described more fully hereinafter.

Master pin

65 At least one pivotal connection of the endless track, between one of the pairs of links of an assembly and the links of an adjacent assembly, includes a master connecting element constructed to have a readily releasable connection with 70 one pair of the links to permit facile assembly or disassembly of the entire track. Heretofore, specially constructed master links have been included in the track for this purpose. In our invention, at least one of the link connecting 75

pins is specially constructed to provide by itself the master connecting element, thus permitting all the links forming the same rail of the track to be of like construction and completely interchangeable.

Master pin 121 (Figs. 1 and 6) has end recesses 122, preferably of frusto-conical taper; the end of the pin about each recess 122 being slotted at 123. Tapered plugs or wedges 124 are driven into recesses 122 to expand the ends of pin 121 so as to wedge securely such recessed ends within track links 107 and 108; the slots 123 facilitating expansion of the pin ends for this purpose. Each plug 124 is preferably provided with threaded aperture 126 in the outer end thereof, to receive a suitable implement for extracting the plug when it is desired to disassemble the track. Threaded aperture 126 in plug 124 also allows the use of a cap screw or the like which can be screwed into the aperture until its head contacts the outer end of the plug, to provide an abutment head against which a hammer or the like can be struck for driving the plug into place without injury to the threads thereof.

After assembly, aperture 126 is preferably sealed by plug 127 of cork or other readily removable packing material, to prevent entry of mud, dirt and the like. It is to be noted that the ends of master pin 121 do not extend outwardly beyond the outer sides or faces of track links 107 and 108. Therefore, it cannot interfere with the outside track roller flanges employed by us.

Track link and rail

The spaced oppositely positioned track links of each link assembly, although similarly formed as to structural features, differ only in being right-hand and left-hand rail forming links. As the structures are similar, only the right-hand link will be described in detail; it being understood that the left-hand link corresponds thereto in every structural feature.

Track link 108 (Figs. 7 and 8), for the purpose of providing strength, is preferably an integral metal forging, which is thereafter formed to provide a finished track link by certain simple machining operations. By a special construction of the link and a special arrangement of the forging parting line along the link, certain desirable features are imparted to the link without the use of special machining operations. Only conventional machining operations are desirable after the link is forged, namely, to form a flat shoe engaging surface on the outer edge of the link, a flat planar rail surface on the inner edge thereof, to finish the apertures which receive the track pin and the track bushing, and to provide tapped holes for the cap screws which secure the track shoe to the links.

Each link has a rail the intermediate portion of which is of full rail width; and end portions of the link are of reduced rail width. One reduced width end portion has a side edge forming a straight line continuation of one side edge of the intermediate full width rail portion, while the opposite reduced width end portion has a side edge which forms a straight line continuation of the opposite side edge of the full width rail portion. Thus, at each end of the link, there is a recess at one side thereof and a reduced width end portion at the opposite side, to enable adjacent links of a track to be butt-lap fitted and pivotally connected for the provision of full width rail joints. The extremities of the reduced width

end portions are formed to cooperate with adjacent links, to provide rail surfaces throughout the joints of the character previously discussed, and which will be pointed out more specifically hereinafter.

With particular reference to Figs. 2, 7 and 8, the link construction comprises inner link edge portion 131 of the desired depth to provide sufficient material for the rail portion of the link. Intermediate portion 132 of rail portion 131 is of substantially full rail, uniform width, namely, the maximum rail width of the entire rail formed by a plurality of links connected end to end. Rear end portion 133 is at the outer side of the link and is of reduced uniform width; and its outside rail edge portion 133a forms a straight continuation of the outside rail edge portion 132a of intermediate portion 132. Thus, an end recess 133' (Fig. 9) is provided at the rear end of the link adjacent reduced portion 133. Front end reduced width portion 134 is at the inner side of the link, and is consequently diagonally opposite to reduced width portion 133; end recess 134' (Fig. 9), diagonally opposite end recess 133', being formed at the end of the link adjacent reduced portion 134. Reduced portion 134 has inside rail edge portion 134b forming a straight continuation of inside rail edge portion 132b of intermediate portion 132. Outside rail edge portions 132a and 133a are substantially parallel to inside rail edge portions 132b and 134b. Hence, each link has parallel side edges forming the side edges of the rail.

Each of reduced width end portions 133 and 134 is of substantially one-half full rail width, thus enabling adjacent links to be connected together, in the manner shown in Fig. 2, to provide butt-lap rail joints of substantially full, uniform rail width.

Outer edge portion 135 (Figs. 7 and 8) of the link provides the track shoe engaging portion, and has flat surface 136 to engage track shoe 106. In the front reduced width end portion 134 of the link, rail portion 131 and shoe portion 135 are integral with bushing receiving eye or boss 137 formed with machined aperture 138 for a link connecting bushing; while in the rear reduced width end portion, portions 131 and 135 are integral with pin receiving boss or eye 139 formed with machined aperture 140 for a link connecting pin. Centrally thereof, the link is apertured to allow for escape of foreign material as the track operates; the apertured portion being braced by intermediate reinforcing web 146 integrally joined to rail portion 131 and to shoe portion 135. Thus, apertures 147 and 148 extend from one side face of the link through the other side face. Such apertures are not obstructed by the fastening means securing shoe 106 to the link, because the heads of cap screws 109 engage shoe 106; and their threaded ends, secured in shoe engaging portions 135 of the link, do not project into apertures 147 and 148. Consequently, the full size of apertures 147 and 148 is available to allow escape of foreign material.

As seen in Figs. 9 and 10, reinforcing web 146 is shaped so as to offer minimum resistance to the escape of foreign material, which occurs as the driving sprocket teeth engage the link connecting bushings in the travel of the track around the sprocket. For this purpose, edge portion 149 of the web adjacent the inside face of the link is made much narrower than edge portion 149a facing the outside of the link; and side faces 150 of the web are perfectly smooth and planar.

Preferably, the web is of triangular cross section, with the apex thereof at the inside of the link; the smooth, planar sides 158 diverging outwardly toward the wider outside edge 149a.

The extremities of reduced width end portions 133 and 134 are specially formed to cooperate with adjacent links to provide our novel wear-taking, rail-joint construction. Reduced width end portion 134 has an end boss 151 forming a rail end projection; and reduced width end portion 133 has a similar rail end projection boss 152. Projection 151 (Fig. 7) is formed with a convex substantially frusto-conical surface 156 generated about the axis of aperture 138. Consequently, surface 156 is obliquely disposed with respect to the axis of aperture 138 and to the longitudinal line of the track or rail. It is also obliquely disposed with respect to the line of contact which a track roller makes with the rail as it travels thereover, and to both the parallel side rail edges 132a and 132b of the full width rail portion 132. The part of convex surface 156 of greatest radius is at outside edge 134b of reduced width end portion 134, to cause such surface to slant inwardly from the outside edge.

Each oblique convex surface 156 of one link is adapted to underlap a complementary oblique concave surface formed underneath the rail surface of the full width rail portion 132 of the adjacent link. As seen in Figs. 2 and 8, such complementary oblique concave surface is indicated at 157. Surface 157 is at the same side of the link as surface 156, and is of frusto-conical shape; the axis of generation being coincident with the axis of aperture 140. Also, surface 157 is substantially parallel to surface 156. Surfaces 156 and 157 are of such complementary shape that the distance between any selected corresponding points thereof (distance A, for example, in Fig. 8 taken between two points lying in a line parallel to a side edge of the rail), is substantially the same. Such distance, as illustrated by example line A, is also substantially equal to the pitch of the track link; the pitch being indicated by line B in Fig. 8. The pitch line is only sufficiently greater to provide for clearance between surface 157 of one link and complementary surface 156B of an adjacent link. In the example of link shown, the pitch B is 8 inches, and the distance A is substantially 7.75 inches so that a total clearance of about .25 inch obtains to allow pivotal movement between adjacent links.

From the preceding description, it is seen that at one side of the rail of the link are formed a convex oblique surface at one end and a complementary concave surface at the opposite end; the convex surface of one link being adapted to underlap the concave surface on an adjacent link. The opposite side of the rail is also similarly provided with complementary oblique surfaces. Projection 152 is formed with convex, substantially frusto-conical surface 161 (Figs. 2 and 8) slanting inwardly from the outside edge 133a of reduced width portion 133; and complementary oblique concave surface 162 is formed under the rail surface of the full width rail portion 132 to be underlapped by a complementary convex surface on an adjacent link. Surfaces 161 and 162 are also parallel; and the distance between any selected corresponding points on surfaces 161 and 162 is substantially equal to the distance between any such points on surfaces

generated about the axis of the link aperture 138 or 140 adjacent to such surface.

With particular reference to Figs. 2, 7 and 8, it will be noted that oblique convex surface 156 terminates at the rail surface in a similarly oblique or diagonally disposed rail end edge 171; and oblique concave surface 157 terminates at the rail surface in similarly oblique rail end edge 172 parallel to rail end edge 171. Oblique surfaces 162 and 161 terminate similarly in obliquely disposed parallel rail end edges 173 and 174; all of edges 171, 172, 173 and 174 being parallel with respect to each other and lying substantially in the plane of the rail surface of the link, to provide the end edges of the rail surface of the link. In this connection, it will be observed (Fig. 9) that edges 172 and 173 form edges which cooperate to bound, respectively, end recesses 133' and 134'; the end recesses being adapted to receive reduced width end portions of adjacent links.

The described construction of each link enables adjacent links, as previously pointed out, to be connected end to end to provide butt-lap joints of substantially full rail width. Particular reference is made to Figs. 1, 2 and 3 in the following detailed description of the rail joint between adjacent links. In Fig. 2, the links to the left and right of link 108 and their parts corresponding to those already described for link 108, are indicated by the same reference numerals. However, the left link and its parts are distinguished by letter B and the right by letter A.

Because the distance between corresponding points on surfaces 156 and 157, and on surfaces 161 and 162, is substantially equal to the pitch of the link, the links can be connected with oblique concave surface 162B under the rail surface of the full width rail portion of link 108B, substantially parallel to and in close proximity to complementary oblique convex surface 161 on reduced width end portion 133 of link 108. The oblique rail end edges 173B and 174 are substantially parallel and closely spaced apart, so that the end of edge 174 which is adjacent the side edge of the rail, or, in other words, the outer end portion, overlaps the inner end portion of the adjacent rail end edge 173B. Also, the outer part of surface 161 overlaps the inner part of surface 162B. Furthermore, by virtue of the projection boss 152 on which convex surface 161 is formed, the concavity at concave surface 162B under the full width rail surface of link 108B, is substantially completely filled by the boss. The relationship which exists between the other complementary curved surfaces and rail end edges of adjacent links is the same as that described, as is shown in Fig. 2.

Thus, each rail joint between ends of two adjacent links, by virtue of the oblique extremities formed on the cooperating and overlapping reduced width end portions on such links, comprises two pairs of substantially parallel and obliquely disposed rail end edges and surfaces. One of such pairs, for example, comprises oblique rail end edges 173B and 174 and the oblique curved surfaces associated therewith, which extend from the outside edge of the rail to a location between the side edges of the rail; and the other of such pairs comprises edges 171B and 172 and the surfaces associated therewith, which extend from the inner or opposite side edge of the rail to another location between the side edges.

It will be noted from Fig. 2 that the angle of

adjacent rail end edges 173B and 174 with respect to the longitudinal line of the rail or the line of contact of a track roller with the rail, and the spacing between such edges, is such as to enable 5 more than half full rail width surface support for the track roller 34 (illustrated diagrammatically in Fig. 5) throughout its travel over an entire rail joint or pivotal connection between ends of adjacent links. For illustration, line X indicates 10 the line of contact of the roller with the rail, just at the point where the outside end portion of the roller passes over the outer portion of the gap between rail end edges 173B and 174. At this position, it will be observed that substantially all 15 of the roller is supported on the rail surface of link 108B and adjacent both side edges of the rail. As the roller proceeds in the direction of arrow W, it is seen, as indicated by line of contact Y, that before it passes completely over edge 173B, it finds 20 support on reduced width portion 133 of link 108 closely adjacent the outside edge of the rail, and is still supported adjacent both side edges of the rail.

When the roller travels to the location where it 25 just passes completely over edge 173B, indicated by line of contact Z, it still finds support adjacent both side edges of the rail, and on both reduced width portions 133 and 134B. The action at the other spaced edges 171B and 172 of the joint will 30 be obvious from the preceding explanation.

In other words, the line of contact (line Y for example) as it traverses a portion of the extremity of reduced width end portion 133 of link 108 also traverses a portion of the adjacent link 35 108B. Materially increased unit pressure on a reduced width end portion 133 or 134B is therefore obviated, to eliminate more rapid wear of such portion as the roller passes over the rail gap adjacent thereto. This results in substantially complete 40 elimination of the roller pounding action which has heretofore existed, to increase materially the life of the rail. Furthermore, because of the provision of the projecting bosses 152 and 154 upon which, respective convex oblique surfaces 161 and 156 are formed, and which substantially 45 fill the concavities under adjacent links cooperating therewith, sufficient material obtains to provide ample support for the rollers over the joint gaps. In comparison with joints which have 50 heretofore characterized endless self-laying track constructions, we have found that the improved joint construction of our invention serves to increase the life of the track materially; the average increase of life being about 25%.

55 A joint of the character described wherein substantially constant and uniform spacing exists between the opposing end surfaces during flexing of the joint as pivotal movement between connected links occurs, is termed in the art, a wiping joint, from the fact that foreign material tending to lodge in the space between such surfaces of the joint and act as a wedge to spread the elements, cannot enter during the pivotal flexing and is wiped away by the action of the cooperating wiping surfaces of the joint. The oblique character of such surfaces presents the added advantage of greater wiping area, besides providing a joint between links enabling the gradual transfer of load on the rails as the track rollers 60 travel from link to link, which is of the utmost importance in adding to the useful life of the track, as noted above.

The above construction can be readily obtained in a forged track link, without special machining operations, by having the parting line resulting

from forging, placed in an advantageous location. To accomplish the above purpose, the parting line along the rail portion of the link, indicated at C in Figs. 2 and 9, is formed to extend for a short distance, from end point D, substantially 5 parallel to and closely adjacent the outer side of the link to point D' beyond edge 174, then diagonally across the rail surface to point E' ahead of edge 171, and then substantially parallel to and closely adjacent to the inner side of the link to 10 point E. Points D and E are located at the outermost parts of respective oblique surfaces 161 and 156. Thus, the parting line along the rail surface has extremities or end portions on oblique surfaces 161 and 156; and such line extremities 15 lie in vertical planes which are very close to and substantially coincide with the respective side faces of the link. The spacing of the parting line from the side faces of the links is made as small as possible at the ends of the link; such spacing 20 being just enough to provide sufficient depth for good filling of material in the die during forging. In this connection, it will be observed that the outer portions of diagonally opposite end surfaces 156 and 161 are slightly bevelled as indicated at M to facilitate filling.

Across the bottom or track shoe engaging face of the link, the parting line is indicated at F in Fig. 10. It is seen (Figs. 9 and 10) that the parting line around the front end of the link lies entirely 30 in a vertical plane closely adjacent the inner face or side of the link; while the parting line at the rear end of the link passes from point D adjacent the outer face of the link diagonally down line G to point H on the pitch line of the 35 link (Fig. 8) and adjacent the inner face of the link (Figs. 9 and 10). In Figs. 9 and 10, the parting line on the interior surfaces of the link, formed by apertures 138, 140, 147 and 148, is indicated at J and K.

The endless track of our invention is designed to cooperate with track rollers having outside roller flanges only, namely, flanges which engage only the outside edges of the spaced rails which form each endless track. This avoids flange interference with the track bushings, heretofore characterizing constructions with inside track roller flanges, and enables the provision of increased bushing diameter between the rails for obtaining strength of construction. The outside 45 faces of the track links are formed free of projections which would, otherwise, cause interference with such outside roller flanges as wear occurs on both the rollers and the rails.

As seen in Figs. 5 and 7, the outer end of boss 55 139 which receives the link connecting pin, is so disposed with respect to the outside edge of the rail thereover, as to preclude interference with outside track roller flange 179 as wear occurs. The end of the boss lies in substantially the same 60 upright plane as the outside edge of the rail; and the outside edge of the rail is bevelled at 181 and a portion of boss 139 is similarly bevelled at 181A, to provide a desirable slanting face portion for cooperation with complementary bevelled or slanting 65 inside face 181' of track roller flange 179. Relief groove 184 is formed in the outside face of the link between bevelled surfaces 181 and 181A, to avoid any possibility of flange interference, and to reduce weight inasmuch as the additional material 70 is not required for providing strength. Thus, the outside track roller flanges 179 can be made sufficiently long to hold the rollers on the rails of the track. Preferably, we employ outside roller flanges long enough to overlap the portions of 75

bosses 139 adjacent the rails and to overlap the portion of bushings 113 between the rails.

Since only outside roller flanges are employed and because the outside faces of the links are formed to preclude flange interference, the material utilized to provide the wear taking portion of the rail need be only of a depth sufficient to provide for such wear; no excess depth being necessary (as would be the case where inside roller flanges are employed) to avoid premature interference of inside roller flanges with bushings 113 after wear on the rails and track rollers. Consequently, saving in weight of the link is effected; and, also, the full depth of the rail portion is available for wear, thus materially increasing the life of the track in comparison with self-laying tracks heretofore employed. The average increase of life by virtue of the outside roller flanges only, and the outside face link construction which avoids interference with such outside flanges, is about 25% and since the improved joint construction increases the life of the track about 25%, it is seen that the total average increase of track life enabled by such two features, is about 50%.

25 Elimination of inside track roller flanges also enables enlargement, whenever desirable, of the diameter of the portion of each bushing 113 between the rails, to provide strength of construction. In the track mechanism chosen for illustration and which is adapted for use with a tractor designed for heavy duty work, such as bulldozing, we employ bushings 113 of enlarged diameter between the rails. However, increased height of the link and consequent increase in weight thereof, is avoided by providing reduced diameter ends 186 (Fig. 4) on each bushing 113; such ends being press-fitted in the links of each pair. Also, reduced bushing ends 186 enable the pitch line to be maintained a minimum practical distance above 30 the ground. This is so because if increased diameter bushings of constant diameter from end to end were employed, the diameter of bushing bosses 137 would have to be made larger, with consequent increase in height and weight of the link, and 45 increase in height of the pitch line above the ground.

The total height of each link is, therefore, determined solely by two factors; first, the thickness of bushing boss 137 (Fig. 7) at the bottom thereof to 50 provide sufficient strength for withstanding stresses; and, secondly, in addition to the thickness provided at the bottom, a rail portion at the top of sufficient depth of material to provide for wear, such rail portion being indicated by the 55 portion above line 187 in Fig. 7.

SUMMARY

From the foregoing description, it is seen that many features of our invention cooperate in providing an improved wear-resisting track mechanism capable of having long life. The improved rail joint construction is one of such features. Another feature is the provision of outside track roller flanges only and the elimination of inside 65 roller flanges, which also enables minimum practical depth of material for the rail portion of each link, particularly in view of the fact that the outside faces of the links are shaped to avoid interference with such outside track roller flanges upon 70 wear of the rollers and track. Bushings of increased diameter between the rails cooperate to provide for strength; and the reduced ends thereof enable minimum spacing of the pitch line above the ground and also minimum over-all height of 75 the link.

Therefore, we claim as our invention:

1. A link for an endless self-laying track having a full width rail portion for supporting a weight bearing roller, and a portion at each end of such link of reduced width for pivotal cooperation with a corresponding part of an adjacent link, the extremities of such end portions being formed to cooperate with adjacent pivotally connected links to provide a rail surface throughout each pivotal connection of more than one-half the full width 10 of the rail portion.

2. A link for an endless self-laying track having a rail portion of full uniform width for supporting a weight bearing roller, and a portion at each end of such link of reduced width for pivotal cooperation with a corresponding part of an adjacent link to provide with such part a rail joint of substantially the same uniform width as that of the rail portion, the extremities of such end portions being formed to cooperate with adjacent pivotally connected links to provide a rail surface throughout each pivotal connection of more than one-half the full width of the rail portion.

3. A link for an endless self-laying track having a full width rail portion for supporting a weight bearing roller, and a portion at each end of such link of reduced width for pivotal cooperation with a corresponding part of an adjacent link, each of said end portions having at its extremity a rail end edge disposed obliquely with respect to a side edge of the full width rail portion to cooperate with a complementary oblique edge of an adjacent pivotally connected link to provide an oblique wiping joint.

4. A link for an endless self-laying track having a full width rail portion for supporting a weight bearing roller, and a portion at each end of such link of reduced width for pivotal cooperation with a corresponding part of an adjacent link; each of said end portions having at its extremity a rail end edge disposed obliquely with respect to a side edge of the full width rail portion, and a similarly oblique convex surface formed adjacent the rail surface thereof to underlap the full width rail portion of an adjacent 40 pivotally connected link.

5. A link for an endless self-laying track having a full width rail portion, a portion at each end of the link of reduced width and having a rail projection adjacent the rail surface thereof, each projection being formed with a convex curved surface, and a concave surface formed at each end of the link under the rail surface of the full width rail portion, all of said curved surfaces being disposed obliquely with respect to a side 50 edge of the full width rail portion and terminating in similarly oblique substantially parallel edges providing end edges of the rail surface, each convex surface at an end of the link being of a shape complementary to that of the concave 60 surface at the opposite end of the link to enable said link to be connected to like links with adjacent end edges and adjacent curved surfaces of adjacent links substantially parallel and in close proximity.

6. An endless self-laying track comprising a plurality of connected links, each link having an intermediate full width rail portion and end portions of reduced width cooperating with reduced width end portions of adjacent links to provide 70 butt-lap rail joints of full rail width throughout; each joint including a pair of adjacent oppositely disposed rail end portions extending in thickness from one side edge of the rail to a location between the side edges of the rail, and another 75

pair of adjacent similarly disposed rail end portions extending in thickness from the opposite side edge of the rail to another location between the side edges of the rail, said oppositely disposed end portions being so spaced and angularly positioned with respect to the longitudinal line of the rail as to provide throughout the joint a rail surface of more than one-half the full rail width.

7. A forged metal link for an endless self-laying track having a full width rail portion, and a portion at each end of such link of reduced width; the forging parting line along the rail surface of the link having an end portion at one side of the link and another end portion at the opposite side of the link, each end portion of such line being closely adjacent to a side of the link.

8. A forged metal link for an endless self-laying track having a full width rail portion, a portion of reduced width at one side and end of the link, and another portion of reduced width at the opposite side and end of the link, each of said end portions having adjacent its extremity a surface oblique to a side edge of the full width rail portion; the forging parting line along the rail surface of the link having end portions on said oblique surfaces, each of such line end portions being closely adjacent and substantially parallel to a side of the link.

9. A forged metal link for an endless self-laying track having a full width rail portion, a portion of reduced width at one side and end of the link, and another portion of reduced width at the opposite side and end of the link, the outside edge of each of such end portions forming a straight and smooth continuation of a side edge of the full width rail portion, each of such end portions having adjacent its extremity a convex surface slanting inwardly from the outside edge thereof; the forging parting line having portions closely adjacent to the outside edges of such convex surfaces.

10. A link for an endless self-laying track having a full width rail portion, a portion adjacent one side and end of the link of reduced width and having a rail projection continuous therewith, said reduced width portion including said rail projection having a surface lying in the plane of the rail surface of said full width rail portion, a second portion adjacent the opposite side and end of the link of reduced width and also having a rail projection with a surface in the plane of said full width rail surface, each projection terminating in a surface extending obliquely inwardly from adjacent the associated side of the link, an oblique surface formed under and adjacent the rail surface of the full width rail portion at a location adjacent said one end of the link and adjacent the side opposite the reduced width rail portion which is adjacent said one end of the link, and a second oblique surface formed under and adjacent the rail surface of the full width rail portion at a location adjacent said opposite end of the link and adjacent the side opposite the second reduced width rail portion which is adjacent said opposite end of the link, each of said oblique surfaces under the full width rail portion of the link extending obliquely outwardly from adjacent the associated side of the link, the oblique surfaces at the same of each of opposite sides of the link being of substantially complementary shape to provide the same distance between any selected corresponding points thereof, whereby said link can be pivotally connected with similar links with each oblique surface on a rail projection underlapping the associated oblique surface formed under the full width rail surface of an adjacent similar link to thereby provide long wearing rail joints; the forging parting line along the rail surface of the link having end portions on the oblique surfaces on the rail projections, each of said line end portions being closely adjacent and substantially parallel to a side of the link whereby the forged link can be removed from the die even though such oblique surfaces extend inwardly.

11. A forged metal link for an endless self-laying track having a full width rail portion, a portion adjacent one side and end of the link of reduced width and having a rail projection adjacent the rail surface thereof, a second portion adjacent the opposite side and end of the link of reduced width and having a rail projection adjacent the rail surface thereof, each projection terminating in a surface extending obliquely inwardly from adjacent the associated side of the link in addition to having a surface lying in the plane of the rail surface of said full width portion, an oblique surface formed under and adjacent the rail surface of the full width rail portion at a location adjacent said one end of the link and adjacent the side opposite the reduced width rail portion which is adjacent said one end of the link, and a second oblique surface formed under and adjacent the rail surface of the full width rail portion at a location adjacent said opposite end of the link and adjacent the side opposite the second reduced width rail portion which is adjacent said opposite end of the link, each of said oblique surfaces under the full width rail portion of the link extending obliquely outwardly from adjacent the associated side of the link, the oblique surfaces at the same of each of opposite sides of the link being of substantially complementary shape to provide the same distance between any selected corresponding points thereof, whereby said link can be pivotally connected with similar links with each oblique surface on a rail projection underlapping the associated oblique surface formed under the full width rail surface of an adjacent similar link to thereby provide long wearing rail joints; the forging parting line along the rail surface of the link having end portions on the oblique surfaces on the rail projections, each of said line end portions being closely adjacent and substantially parallel to a side of the link whereby the forged link can be removed from the die even though such oblique surfaces extend inwardly.

12. A link for an endless self-laying track having a full width rail portion, a portion at an end of the link of reduced width and having a rail projection adjacent the rail surface thereof to extend said rail surface substantially across the gap which would otherwise occur between connecting links of a similar type having a full width rail portion and a less than full width rail portion.

13. A link for an endless self-laying track having a full width rail portion, a portion at an end of the link of reduced width and having a rail projection adjacent the rail surface thereof to extend said rail surface substantially across the gap which would otherwise occur between connecting links of a similar type having a full width rail portion and a less than a full width rail portion, said extended surface having at its extremity a boundary which is oblique to the perpendicular to the side boundaries of said full width portion of said rail surface.

14. A link adapted for pivotal connection with similar links to form an endless self-laying track having a rail surface for supporting a weight bearing roller, comprising an intermediate portion of full rail width, and portions of less than full rail width extending from diagonally opposite corners of said full rail width portion, each of said less than full width portions being

- continuous with said full width portion and having a rail surface lying substantially in the plane of the rail surface of said full width portion and terminating adjacent the end thereof in a wiping surface obliquely disposed with respect to the sides of said link, each of the unextended end portions of said intermediate full width portion having an oblique wiping surface in complementary relationship with the oblique wiping end surface of that less than full width portion adjacent the same side of said link for providing an oblique wiping joint between successive links.
15. A link adapted for pivotal connection with similar links to form an endless self-laying track having a rail surface for the support of a weight bearing roller, said link having at least a portion adjacent one end terminating in a convex curved surface oblique to the side walls of said link and a portion adjacent the opposite end terminating in a concave curved surface the curvature of which is complementary to said first curved oblique surface to provide an oblique wiping joint between connected links.
16. A track-type tractor track link adapted for pivotal connection with similar links and having a full width rail portion and end portions of reduced width at diagonally opposite corners, each of the portions of reduced width terminating at its extremity in a convex oblique surface and an oblique edge at the rail surface, and the full width rail portion of the link terminating at diagonally opposite corners thereof in oblique edges at the rail surface from which extend oblique concave surfaces lying underneath the rail surface of said full width rail portion, the curvature of the oblique surfaces at each side of the link being substantially complementary and the distances between corresponding points on the oblique surfaces at either side of the link being substantially the same as that between similar points on the oblique surfaces at the opposite side of the link to provide a diagonal wiping joint at each extremity when said link is pivotally connected with links of similar construction.
17. A forged track-type tractor track link adapted for pivotal connection with similar links and having a full width rail portion and end portions of reduced width at diagonally

opposite corners, each of the portions of reduced width terminating at its extremity in a convex oblique surface and an oblique edge at the rail surface, and the full width rail portion of the link terminating at diagonally opposite corners thereof in oblique edges at the rail surface from which extend oblique concave surfaces lying underneath the rail surface of said full width rail portion, the curvature of the oblique surfaces at each side of the link being substantially complementary and the distances between corresponding points on the oblique surfaces at either side of the link being substantially the same as that between similar points on the oblique surfaces at the opposite side of the link to provide a diagonal wiping joint at each extremity when said link is pivotally connected with links of similar construction, said link having a forging parting line close to a side wall of said link at each end.

18. A link adapted for pivotal connection with similar links to form an endless self-laying track having a rail surface for supporting a weight bearing roller, comprising an intermediate portion of full rail width, and portions of less than full rail width extending from portions of opposite ends of said full rail width portion, each of said less than full rail width portions being continuous with said full rail width portion and having a rail surface lying substantially in the plane of the rail surface of said full rail width portion and terminating adjacent the end thereof in a wiping surface obliquely disposed with respect to the sides of said link, each of the unextended end portions of said intermediate full rail width portion having an oblique wiping surface shaped to complement the wiping surface on an adjacent less than full rail width portion of an adjacent similar link to be pivotally connected thereto and each of the oblique wiping surfaces on the less than full rail width portions of said link also being shaped to complement the wiping surface on the adjacent unextended end portion of an adjacent similar link to be pivotally connected thereto for providing an oblique wiping joint between successive links.
